UNITED STATES PATENT OFFICE.

KIRK K. WRIGHT, OF BUFFALO, NEW YORK.

MOTOR SUPPORT FOR BOTTLE-WASHING MACHINES.

Application filed January 5, 1926. Serial No. 79,437.

This invention relates to improvements in bottle washing machines of that kind having a plurality of revolving spindles provided with brushes which are adapted to clean the bottles while they are held by hand.

The objects of the invention are to construct an improved and simplified machine of this type of strong and rugged construction having a motor drive and an improved mounting for the driving motor, which mounting is adjustable for the purpose of increasing the distance between the motor pulley and the driven pulley of the machine to take up the slack in the driving belt; also to provide a splash guard of improved and simplified construction which is adapted to be connected to the motor support, and is movable therewith and also with the motor, and is adapted to surround and guard the driving belt and motor pulley and at the same time protect or shield the ventilating openings in the adjacent end of the motor against the entrance of water thrown in the direction of these parts in the use of the machine; and also to improve the construction of machines of this kind in the other respects hereinafter specified and claimed.

In the accompanying drawings,

Fig. 1 is a side elevation of a bottle washing machine embodying the invention, the brushes being omitted.

Fig. 2 is a fragmentary, longitudinal, vertical section on an enlarged scale, showing the adjusting means for the motor supporting bracket or platform of the machine.

Fig. 3 is a face view of the motor bracket or platform.

Fig. 4 is a similar view of one of the side brackets to which the motor platform is adjustably connected.

Fig. 5 is an elevation of the machine, partly in section, on line 5—5, Fig. 1.

The bottle washing machine illustrated in the drawings is provided with a pair of horizontal, spaced and longitudinally extending spindles 10, on which brushes for washing the insides of two bottles simultaneously are secured, and an intermediate, longitudinal spindle 11, which supports a brush for washing the outside surfaces of the two bottles which are being washed by the first mentioned brushes. The brushes are not shown in the drawings. The spindles 10 and 11 extend rearwardly through a lower

splash guard and bearing member 12 projecting upwardly from the base plate 13 of the machine, and the spindles terminate in a gear housing 14 in which are mounted suitable gears (not shown) meshing with one another and secured to the spindles for rotating the brushes. Motion is imparted to these gears through a pulley 15 secured to the spindle 11 outside of the gear housing 14, which, in turn, is driven by an electric motor 16 arranged above the gear housing 14. The motor is provided with a drive pulley 17 secured on the end of its shaft 18, said pulley being operatively connected to the pulley 15 to drive the same by a belt 19.

In accordance with the invention, the motor 16 is operatively mounted on the machine in the following manner.

The gear housing 14 is formed with opposite side walls 20 to each of which is secured an upwardly extending supporting arm or bracket 21. Each bracket has a securing flange 22 adapted to engage one of the walls 20 of the gear housing, and is provided with apertures for the reception of bolts or securing devices 23, whereby it is rigidly secured to said walls 20. The flange 22 terminates at its upper end in an offset portion 24 from which an upwardly directed securing plate or member 25 extends and which is provided with a transverse vertical face 26. This portion 25 and the flange 22 are reinforced by a connecting and stiffening web 27.

A motor supporting platform or bracket 28 extends transversely from side to side of the machine above the gear housing 14 and is adapted to bridge the space between the opposite side brackets 21. This platform or bracket 28 is formed with a top face 29 upon which the motor 16 is secured, as by the bolts 30, and with a depending, transversely extending web 31, the lower edge of which preferably conforms approximately to the shape of the top surface of the gear housing 14. This flange is provided with apertures 32 adapted to register with like apertures 33 in the supporting arms 21, whereby, by passing bolts 34 through the registered apertures, the platform 28 can be secured and held firmly in place on the machine.

A belt hood and splash guard 35 is provided which is adapted to surround the motor pulley 17 and belt 19, being formed with opposite longitudinally extending side

flanges or walls 36 which terminate at their upper ends in a curved wall 37 extending over the upper part of the pulley 17, and a transverse flat wall 38 connecting the side walls or flanges 36. This hood and guard, in addition to protecting the operative against injury from the moving belt 19, is also adapted to act as a splash guard to intercept water thrown in the direction of the motor in the use of the machine, and prevent the water from entering the annular series of ventilating apertures 38 in the adjacent end of the motor casing. The guard 35 is constructed and adapted to be rigidly secured to the motor platform 28, and for this purpose is provided with a pair of oppositely extending lateral lugs 40, preferably formed integrally therewith and adapted to engage and be rigidly secured to corresponding integral lugs 41 depending from the motor platform, by suitable bolts or other fastenings 42 extending through registering apertures in the lugs 40 and 41. If desired, the apertures in one of the members, for instance, the apertures 43 of the guard 35, may be in the form of elongated, vertically extending slots, whereby the guard may be initially adjusted and secured in correct relation to the pulley 17 and the belt 19.

In accordance with this invention the motor platform 28 is adjustable vertically relatively to the fixed brackets or arms 21, so that the proper tension of the driving belt 19 may be maintained. For this purpose the registering apertures 32 and 33 in the platform 28 and supporting arms 21 respectively are preferably made in the form of vertically elongate slots, (see Fig. 2) whereby, by loosening the bolts 34, the platform 28 with the motor 16 thereon may be elevated as required to provide the necessary tension on the belt, and, as the combined belt hood and splash guard 35 is rigidly secured to the platform 28, this guard 35 is always moved with the motor 16 and is maintained in correct relation to the motor pulley 17 and belt 19 without the necessity of separate adjustments of the guard.

The adjacent engaging faces 26 of the supporting arms, and the opposite end portions of the motor platform web 31 are preferably formed with transverse, spaced corrugations or ridges 45 and 46 respectively,

which are adapted to interfit so that, in the different adjustments of the platform on the supporting arms, slipping of the motor platform relatively to the brackets is prevented and a rigid and firm connection is insured at all times.

I claim as my invention:—

1. In a bottle washing machine, the combination with a frame, a spindle rotatable in said frame and having a pulley thereon, a motor having a pulley on its shaft, a belt connecting said motor pulley to said spindle pulley for rotating said spindle, of a pair of fixed spaced arms on said frame, a motor platform extending between said arms and adapted to support said motor, an adjustable connection between said platform and said arms adapted to permit said motor to be positioned at different distances from said frame, whereby the belt may be maintained under proper tension, and a belt hood adapted to extend about said belt and substantially encircle said motor pulley, said hood being rigidly connected to said motor platform, whereby said hood is movable with said platform in the adjustments thereof and is maintained in correct relation to said motor pulley and belt.

2. In a bottle washing machine, the combination with a frame, a spindle rotatable in said frame and having a pulley thereon, a motor having a pulley on its shaft, a belt connecting said motor pulley to said spindle pulley for rotating said spindle, of a pair of fixed spaced arms on said frame, a motor platform extending between said arms and adapted to support said motor, an adjustable connection between said platform and said arms adapted to permit said motor to be positioned at different distances from said frame, whereby the belt may be maintained under proper tension, and a belt hood adapted to extend about said belt and substantially encircle said motor pulley, said hood being rigidly connected to said motor platform, whereby said hood is movable with said platform in the adjustments thereof and is maintained in correct relation to said motor pulley and belt, said hood also being positioned adjacent one end of said motor and adapted to act as a splash guard to prevent water from being thrown, against said end of the motor.

KIRK K. WRIGHT.
